UNITED STATES PATENT OFFICE

133,859

DESIGN FOR A FLAG HOLDER

Walter S. Gass, Seward, Nebr.

Application July 17, 1942, Serial No. 107,588

Term of patent 7 years

To all whom it may concern:

Be it known that I, Walter S. Gass, a citizen of the United States, residing at Seward, in the county of Seward and State of Nebraska, have invented a new, original, and ornamental Design for a Flag Holder, of which the following is a specification, reference being made to the accompanying drawing, forming a part thereof.

In the drawing:

Fig. 1 is a side elevational view of a flag holder, illustrating my new design;

Fig. 2 is a front elevational view of the holder; and

Fig. 3 is a plan view of the holder.

I claim:

The ornamental design for a flag holder, substantially as shown.

WALTER S. GASS.
